UNITED STATES PATENT OFFICE.

ERNEST D. STEER, OF NEW HAVEN, CONNECTICUT, ASSIGNOR TO THE OLD COLONY MFG. CO., OF HAMDEN, CONNECTICUT, A CORPORATION.

DESIGN FOR A FABRIC COVER FOR WATER-BOTTLES.

46,704.

Specification for Design.

Patented Nov. 24, 1914.

Application filed August 17, 1914. Serial No. 857,267. Term of patent 3½ years.

To all whom it may concern:

Be it known that I, ERNEST D. STEER, a citizen of the United States, residing at New Haven, in the county of New Haven and State of Connecticut, have invented a new, original, and ornamental Design for a Fabric Cover for Water-Bottles, of which the following is a specification, reference being had to the accompanying drawing, forming part thereof.

The figure is a face view of a fabric cover for water-bottles showing my new design.

I claim:—

The ornamental design for a fabric cover for water-bottles, as shown.

ERNEST D. STEER.
